UNITED STATES PATENT OFFICE.

AUGUST RAPP, OF CHICAGO, ILLINOIS, ASSIGNOR TO THE PULLMAN'S PALACE CAR COMPANY, OF SAME PLACE.

DESIGN FOR THE ORNAMENTATION OF CAR INTERIORS.

SPECIFICATION forming part of Design No. 21,996, dated November 15, 1892.

Application filed March 17, 1892. Serial No. 425,358. Term of patent 14 years.

To all whom it may concern:

Be it known that I, AUGUST RAPP, a citizen of the United States, residing at Chicago, Illinois, have invented and produced a new and original Design for the Ornamentation of Car Interiors, of which the following is a specification.

The leading feature of my design consists in a peculiar configuration or contour given to the clear story, the upper berth, the permanent partition below the upper berth, and the top, arms, and legs of the seat, such contour or configuration consisting substantially in a series of reverse curves joined in the ceiling of the clear story by a slightly-curved line. The clear story has in outline between its windows a band in an outward curve, which is reversed and curves inward, passing over the deck-sill, where it meets the free edge of the upper berth when folded, said upper berth presenting a curved exterior when closed. Springing from the lower edge of the upper berth is the outwardly-curved stationary partition between the lower-berth spaces, the top of the seat being upwardly curved, the arms thereof reversely or inwardly curved, and the legs also being inwardly curved.

My design is shown in the accompanying drawing, which is a perspective view of the interior, showing two lower-berth spaces, two upper berths, and a portion of a lower and upper berth.

In said drawing, A indicates the ceiling of the clear story, having the bands of surface ornamentation B, said bands being continued down the side walls of the clear story, but outwardly curved, as at C. Said bands are also continued over the deck-sill D, but are reversely curved, as shown at E. The upper berth F has the surface bands or ornamenta-

tion at their ends marked G, and the lower surface of the upper berth is curved, the lines being more sharply curved at the margins than in the middle of the berth. The edge of the stationary partition H is inwardly curved 45 and the top of the seat is reversely curved. The arms I of the seats are inwardly curved, as are also the legs J.

Following the lines indicated by the reference-letters above given it will be seen that 50 the design presents to the eye from the viewpoint of the drawing a succession of graceful curves extending from the center of the ceiling of the upper deck, down the side walls of the clear story, around the upper berth, down 55 the stationary partition, over the tops of the seats, and along their arms and legs to the floor.

The particular character of the ornamental figures of the design shown in the drawing 60 may be varied, as my invention consists not in said particular and specific figures, but in the general contour and form given to the several parts above described, the object being to present to the eye an interior which shall 65 be pleasing by reason of the fact that the design is made up of a succession of graceful curves.

Such being the intent and leading feature of my invention I do not limit the same to 70 the exact subordinate details of ornamentation.

I claim—

The design for the ornamentation of a car interior, substantially as herein shown and 75 described.

AUGUST RAPP.
